PUMP

Loran O. Wallen, Menomonee Falls, Wis., assignor, by mesne assignments, to Hydro Mfg. Co. Inc., Milwaukee, Wis.

Application November 22, 1943, Serial No. 511,213

2 Claims. (Cl. 103—41)

The present invention relates in general to improvements in the art of pumping fluids, and relates more specifically to various improvements in the construction and operation of hydraulic pumps or the like.

Generally stated, an object of the present invention is to provide an improved pump which is simple in construction and efficient in operation.

Many different types of hydraulic pumps have heretofore been used extensively for diverse purposes, and in some of these prior pumps the liquid was withdrawn by suction from a supply reservoir past an inlet valve by means of a reciprocable plunger, and was forced by the latter past a discharge valve to a zone of utilization of liquid under pressure from which the liquid could be returned directly to the source of supply past a by-pass valve. While some of these previous reciprocating plunger hydraulic pumps equipped with by-pass return valves, were quite satisfactory in operation, most of them were either too bulky for use in limited quarters, or too complicated to manufacture at reasonable cost, and many of these prior devices were moreover relatively unreliable and inefficient in operation.

It is therefore a more specific object of the present invention to provide an improved hydraulic pump assemblage which is extremely simple and compact in construction, and which is furthermore highly dependable and efficient in use.

Another specific object of this invention is to provide various improvements in the construction and operation of reciprocating plunger liquid pumps equipped with liquid return by-pass means, whereby such assemblages may be manufactured expeditiously and at moderate cost.

Still another specific object of the invention is to provide a simplified pump structure which can be readily assembled and dismantled, all parts of which are conveniently accessible for inspection, and which is adapted for diverse uses.

An additional specific object of my invention is to provide a new and useful power driven pump assemblage which can be maintained in clean and sanitary condition with minimum attention, and which comprises a fewest number of readily machinable and standard parts.

These and other specific objects and advantages of the present invention will be apparent from the following detailed description.

A clear conception of the several features constituting my invention, and of the mode of constructing and operating hydraulic pumps embody-

ing the improvements, may be had by referring to the drawing accompanying and forming a part of this specification wherein like reference characters designate the same or similar parts in the various views.

Fig. 1 is a central vertical section through one of the improved hydraulic pumps showing the same applied to a liquid supply source or reservoir;

Fig. 2 is a transverse horizontal section through the pump of Fig. 1, taken along the line 2—2; and

Fig. 3 is a reduced external side view of the improved pump, showing the pump plunger actuating eccentric applied thereto.

While the invention has been shown and described herein as being especially applicable to a small electric motor driven liquid pump for actuating hydraulic shears or the like, it is not my desire or intent to thereby unnecessarily restrict the utility or adaptations of the improvement.

Referring to the drawing, the improved hydraulic pump assemblage shown therein, comprises in general, a one-piece main casing 5 having therein two parallel vertical laterally spaced outer bores 6, 7 and an intermediate upright bore 8, the bores 6, 8 being connected at their lower ends by a horizontal passage 9 and the bores 7, 8 being likewise connected intermediate their ends by a by-pass passage 10; a cylindrical pump plunger 11 reciprocable within the outer bore 6 in any suitable manner, as by means of a revolving eccentric 12; a liquid outlet pipe 13 communicating with the upper extremity of the intermediate casing bore 8 and being connected to a zone of utilization of liquid under pressure, not shown; a relief valve piston or rod 14 adjustable within the outer bore 7 to control the delivery of liquid from the bore 8 through the passage 10 to a liquid return port 15 disposed in line with the passage 10; a ball type discharge or pump outlet valve 16 disposed in the lower end of the bore 8 and being communicable with the passage 9; a poppet type suction or inlet valve 17 mounted in a separable fitting 18 at the extreme lower end of the pump bore 6; and a liquid supply reservoir 19 within which the casing 6 is suspended by means of a removable reservoir cover plate 20.

The main pump casing 5 may be formed by casting or otherwise, and is provided with an upper integral suspension flange 21 which may be detachably secured as by bolts to the reservoir cover 20 so as to permit quick removal of the pump unit; and the bores 6, 7, 8, passages 9, 10, and

port 15 may readily be formed by simple drilling operations. The intermediate bore 8 is preferably sufficiently large for proper reception and operation of the discharge valve 16, and the outer end of the passage 9 may normally be closed and sealed by means of a pipe plug 22.

The reciprocable pump plunger 11 which is snugly fitted within the upright bore 6, is provided at its lower extremity with a cup-packing 24 and has its medial portion provided with an annular recess 23 having a drainage port 23', and this plunger 11 may be rotated about its central axis so as to permit varied disposition of the driving eccentric 12, see Figs. 1 and 3. This eccentric 12 may be driven by an electric motor mounted upon the reservoir cover 20, or from any other suitable source of power; and is connected to the plunger 11 by means of a connecting rod 25 as shown in Fig. 3. The liquid discharge pipe 13 may be caused to communicate with a hydraulic servo-motor for actuating a shear blade, or with a hydraulic ram, or similar device wherein liquid under pressure is supplied by a pump and from which the pressure is relieved through a by-pass to the same reservoir 19 which supplies the pump with liquid. The relief valve piston or by-pass rod 14 is snugly fitted within the bore 7 of the casing 5, and may be adjusted along this bore in any suitable manner so as to either close or open the liquid return port 15; and the lower extremity of the bore 7 is provided with a small pressure relief and drainage opening. The valve rod 14 while being snugly fitted within the bore 8, is also preferably provided with an annular recess 26 for decreasing danger of leakage therealong, and which likewise has a drainage port 26', see Figs. 2 and 3. A set screw 25' coacts with the recess 26 so as to prevent the rod 14 from being lifted out of the bore 7 by liquid pressure.

The ball discharge valve 16 which is movable within the medial bore 8, is normally pressed against its seat by means of a helical compression spring 27 which reacts against the lower end of a fitting 27', and the plug 22 and fitting 27' may be removed to permit free access to the port 9, and to the valve 16 and spring 27. The fitting 18 upon which the suction valve 17 is mounted, is also detachably secured to the main casing 5 by means of several cap screws 28, and is provided with inlet ports 29 communicating with the interior of the liquid supply reservoir 19. The poppet inlet valve 17 is normally held against its seat on the fitting 18 by a helical compression spring 30 coacting with a pin 31 piercing the valve stem, but these springs 27, 30 may be omitted when the pump is being operated at slow speed and in vertical position. The liquid supply reservoir 19 with which the ports 15, 29 communicate may be of any desired shape and capacity, but should always be provided with an abundant supply of liquid 32 the level of which should be maintained well above the port 15 in order to prevent air from entering the pressure system.

During normal operation of the improved hydraulic pump assemblage, after the supply reservoir 19 has been supplied with liquid 32, the pump plunger 11 may be reciprocated with the aid of the revolving eccentric 12 thereby causing successive batches of liquid to be withdrawn from the reservoir 19 past the inlet valve 17 during the suction strokes, and also causing these batches to be delivered past the outlet valve 16 during the discharge strokes. The by-pass valve

rod 14 may be adjusted to assume any desired position within the bore 7 and if this rod is lowered so as to cut off communication between the passage 10 and ports 15, then the liquid passing the discharge valve 16 will be delivered to the bore 8 and outlet pipe 13 under pressure. If, however, the by-pass valve 14 is open while the pump plunger 11 is reciprocating, then the liquid passing the discharge valve 16 will be subjected to only slight pressure sufficient to overcome the tension of the spring 27, and the liquid delivered to the bore 8 will return to the reservoir 19 through the passage 10 and return port 15 for recirculation. When the pump plunger 11 is at rest, the by-pass valve or rod 14 may also be utilized to relieve the pressure existing in the zone of liquid pressure utilization, thus making the hydraulic system extremely simple but flexible in operation.

When it becomes desirable to inspect or remove any of the parts of the pump assemblage, the unit may be removed from the reservoir 19 and the plunger 11, rod 14 and pipe 13 may be disconnected from the structures normally associated therewith, whereupon the plunger 11 may be freely withdrawn from its bore 6 and the rod 14 may likewise be withdrawn from the bore 8. The pipe plug 22 may then be removed for inspection of the passage 9, and the valve 16 and spring 27 may be conveniently inspected upon removal of the upper fitting 27'. Upon removal of the cap screws 28, the suction valve 17 and its supporting fitting 18 may also be detached from the casing 5, thus permitting rapid and convenient inspection of all parts of the assemblage. Reassembly of the structure may be just as readily effected, and the various bores, passages, ports and chambers may obviously be readily formed by simple drilling operations.

From the foregoing detailed description of the construction and operation of the improved device, it will be apparent that the present invention provides an improved hydraulic pump unit which is extremely simple and compact in construction, and which is moreover highly efficient in operation and flexible in its adaptations. The new pumping units can obviously be readily constructed with the aid of simple tools, and these units because of their limited dimensions may be readily arranged in multiple compact groups wherein all of the units may be driven from a common motor or other power source. The improved structures may also be conveniently assembled or dismantled thus making all parts quickly accessible for inspection, cleaning and repairs; and the simplicity and mode of constructing also facilitates quantity production with interchangeable parts. The improved pump has been found especially well adapted for operating hydraulic shears or the like wherein the shear blade is actuated by a hydraulic servo-motor, but is also adapted for diverse other uses.

It should be understood that it is not desired to limit the invention to the exact details of construction or to the precise mode of use, herein shown and described, for various modifications within the scope of the appended claims may occur to persons skilled in the art.

I claim:

1. In a pump, a unitary casing having three laterally spaced upwardly open parallel upright bores and two vertically spaced transverse bores of which the lower bore connects one outer upright bore with the lower end of the intermediate bore and opens at one side of the casing while the

upper transverse bore connects the medial portions of the intermediate bore with the other outer upright bore and opens at the same casing side, the outer end of said lower transverse bore being plugged and the corresponding end of said upper transverse bore being open while the lower end of said first mentioned outer upright bore is enlarged, a pump plunger reciprocable in said first mentioned upright bore, a suction valve detachably confined within said bore enlargement, a ball discharge valve confined within said intermediate bore between said transverse bores, a tubular discharge fitting screw threaded into the upper portion of said intermediate bore, a helical spring interposed between said fitting and said ball valve, a by-pass control piston slidable within said other outer upright bore and across said upper transverse bore, and a limit stop for said piston coacting therewith within its confining bore.

2. In a pump, a unitary casing having three laterally spaced upwardly open parallel upright bores and two vertically spaced transverse bores of which the lower bore connects one outer upright bore with the lower end of the intermediate bore and opens at one side of the casing while

5 the upper transverse bore connects the medial portions of the intermediate bore with the other outer upright bore and opens at the same casing side, the outer end of said lower transverse bore being plugged and the corresponding end of said upper transverse bore being open while the lower end of said first mentioned outer upright bore is enlarged, a pump plunger reciprocable in said first mentioned upright bore, a suction valve detachably confined within said bore enlargement, a ball discharge valve confined within said intermediate bore between said transverse bores, a tubular discharge fitting screw threaded into the upper portion of said intermediate bore, a helical spring interposed between said fitting and said ball valve, a by-pass control piston slidable within said other outer upright bore and across said upper transverse bore, said piston having a portion of reduced diameter within its confining bore, 15 a limit stop for said piston coacting with said casing and with said reduced piston portion, and ports connecting the upper and lowermost portions of said piston confining bore with the exterior of said casing.
